US00D961993S

(12) **United States Design Patent** (10) Patent No.: **US D961,993 S**
(45) Date of Patent: **** Aug. 30, 2022**

(54) **BEVERAGE CONTAINER**

(71) Applicant: **BRUMIS IMPORTS INC.**, New York, NY (US)

(72) Inventors: **Steven Bram**, New York, NY (US); **Sean Fogarty**, Brooklyn, NY (US)

(73) Assignee: **BRUMIS IMPORTS INC.**, New York, NY (US)

(**) Term: **15 Years**

(21) Appl. No.: **29/682,132**

(22) Filed: **Mar. 1, 2019**

(51) LOC (13) Cl. **07-01**

(52) U.S. Cl.

(57) **CLAIM**

The ornamental design for a beverage container, as shown and described.

DESCRIPTION

FIG. 1 is a side view of a beverage container showing our new design;

FIG. 2 is a rear view thereof;

FIG. 3 is an opposite side view thereof;

FIG. 4 is a top view thereof;

FIG. 5 is a bottom view thereof;

FIG. 6 is a front perspective view thereof; and,

FIG. 7 is a front view thereof.

The broken lines show portions of the beverage container that form no part of the claimed design.
